UNITED STATES PATENT OFFICE

166,425

BELT DISPLAY STAND

Waldo E. Stolz, Dayton, Ohio

Application October 17, 1951, Serial No. 16,972

Term of patent 14 years

(Cl. D80—9)

To all whom it may concern:

Be it known that I, Waldo E. Stolz, a citizen of the United States, residing at Dayton, State of Ohio, have invented a new, original, and ornamental Design for a Belt Display Stand, of which the following is a specification, reference being had to the accompanying drawing, forming a part hereof.

Figure 1 is a perspective view of my belt display stand, showing my new design.

Figure 2 is a side elevational view thereof.

Figure 3 is a top plan view thereof.

I claim:

The ornamental design for a belt display stand, as shown.

WALDO E. STOLZ.
